UNITED STATES PATENT OFFICE.

LAMBERT HERLITSCHKA, OF DUSSELDORF, GERMANY.

CENTRIFUGAL CREAM-SEPARATOR.

SPECIFICATION forming part of Letters Patent No. 661,527, dated November 13, 1900.

Application filed May 19, 1899. Serial No. 717,410. (No model.)

To all whom it may concern:

Be it known that I, LAMBERT HERLITSCHKA, a citizen of the German Empire, and a resident of Dusseldorf, Germany, have invented 5 certain new and useful Improvements in Centrifugal Machines, of which the following is a specification.

This invention relates to a centrifugal machine so constructed that the liquid to be 10 treated is caused to ascend through the entire apparatus, so that a thorough separation of the lighter parts is effected.

In the accompanying drawings, Figure 1 is 15 a vertical central section of my improved centrifugal machine. Fig. 2 is a horizontal section on line A B, Fig. 1; and Fig. 3 is a side view of the liner.

The letter *t* represents a rotatable drum containing a central milk-tube *a*, which receives the milk at its upper end and discharges it from its perforated lower end into a chamber *b*, where the heavier impurities will settle. The sloping roof of this chamber is perforated, as at *c*, and admits the liquid into the lowermost passage of a liner *s*. 25 This liner is composed of a strip of metal bent into the form of a continuous conoidal spiral—*i. e.*, a spiral each winding of which is of truncated conical form. The outer edge of the 30 liner *s* abuts directly against the inner wall

of the drum *t*, and thus a continuous tortuous passage is formed within it. The blue milk escapes by openings *k'* and passage *k* between the upper side of the liner and the bowl-wall. The inner edge of the liner abuts against a 35 tubular jacket *d*, arranged concentric to tube *a*, Fig. 2, and provided with a number of perforations that communicate with the inner open edge of the liner *s*. Thus while the blue milk is by centrifugal action thrown 40 outward to escape at *k* *k'* from the periphery of the liner the lighter cream will separate at the center and will be conducted into the jacket *d* to be ejected through openings *d'*.

What I claim is—

45 A centrifugal machine composed of a rotatable drum, a tubular milk-shaft extending therethrough, a conical spiral liner which abuts at its outer edge against the drum, a perforated jacket that communicates with 50 the inner edge of the liner, and a passage for withdrawing the blue milk from the outer edge of the liner, substantially as specified.

Signed by me at Dusseldorf, Germany, this 1st day of May, 1899.

LAMBERT HERLITSCHKA.
